UNITED STATES PATENT OFFICE.

FRANK SHUMAN, OF PHILADELPHIA, PENNSYLVANIA.

PROCESS FOR UTILIZING WASTE HEAT OF DISTILLATION.

1,014,418.

Specification of Letters Patent.

Patented Jan. 9, 1912.

Application filed December 13, 1907. Serial No. 406,397.

To all whom it may concern:

Be it known that I, FRANK SHUMAN, a citizen of the United States, residing in Philadelphia, Pennsylvania, have invented 5 Improvements in Processes for Utilizing Waste Heat of Distillation, of which the following is a specification.

The object of my invention is to utilize, for the performance of useful work, heat 10 which is now wasted in the operation of stills of various kinds. This object I attain in the manner hereinafter set forth, reference being had to the accompanying drawing, in which—

15 Figure 1 is a diagrammatic representation of apparatus for utilizing waste heat of distillation in accordance with my invention, and Figs. 2 and 3 are sectional views of condensers differing in construction from 20 that shown in Fig. 1, but which may be used in carrying out my invention.

In the operation of oil and other stills it is customary to convey the vapor through 25 a condenser through which water is also caused to flow in a reverse direction, and, although the vapor may at times reach a temperature as high as 600° F. when it issues from the still, the water must be passed through the condenser in such large 30 quantities in order to insure the reduction of the distillate to the desired low temperature that the temperature of the water escaping from the top of the condenser is also at a relatively low temperature. By 35 the exercise of my invention, however, I am enabled to effect the desired reduction in the temperature of the distillate and at the same time am enabled to raise the temperature of a portion of the water used as 40 a cooling agent to such a degree that its heat is available for the performance of useful work, preferably by causing such heated water to vaporize a power-developing agent having a lower boiling point than 45 the water.

In Fig. 1 of the drawing, 1 represents a still of any ordinary character, having a vertical column 2, from the upper end of which vapor escapes through a pipe 3, this 50 pipe being first coiled, as shown at 4, in a condensing vessel 5, and then passing into a condensing vessel 6, in which it is coiled, as shown at 7.

Water enters the lower portion of the condenser 6 through a pipe 9, and a portion of this water, after being heated by contact

with the coil 7, escapes from the condenser 6 through a pipe 10 and enters the lower portion of the condenser 5, in which it is further heated by contact with the coil 4, the heated water then escaping from the condenser 5 through a pipe 11, which terminates in a coil 12 in a generator 13 containing a power-developing agent (such as ether, sulfurous acid, carbonic acid, etc.,) of such character that vapor under pressure can be produced therefrom by the application thereto of such a degree of heat as is possessed by the water in the coil 12, this vapor under pressure being employed 60 to operate a suitable engine 14, and the exhaust vapor being conducted through a coil 15 in a condenser 16 having water-supply and overflow pipes 17 and 19, respectively, the condensed vapor being then returned by 65 means of a pump 20 to the generator 13 to be again vaporized. Instead of passing through a generator coil such as shown, the heated water may be passed through the tubes of a tubular boiler or equivalent device, containing the liquid to be vaporized, the vapor under pressure being used for 70 running any desired form of engine.

The volume of water supplied to the condenser 6 by the pipe 9 is considerably in 75 excess of the volume flowing from the condenser 6 into the condenser 5, this excess escaping from the condenser 6 through a pipe 21, and either running to waste or, if its temperature is high enough, being employed 80 in the same manner as the water escaping from the condenser 5 to vaporize a power-developing agent having a lower boiling point, which agent may be contained in a vessel separate from the generator 13, or 85 the water from the pipe 21 may be conveyed to the lower portion of said generator 13, where the temperature of the power-developing agent is less than that of the water.

It is contemplated to raise the temperature of the water in the condenser 5 to a degree approaching the boiling point, but the temperature of the water escaping from the condenser 6 will, of course, be considerably less, and the amount of condensing 90 water flowing through the condenser 6 can be increased to any desired extent in respect to the amount entering the condenser 5, in order to provide for the desired reduction in the temperature of the distillate 95 escaping from the coil 7, this increased flow of condensing water being preferable to a 100

corresponding increase in the size of the condenser 5, in order that the latter may not exceed reasonable limits. By reason of my invention, therefore, all, or the greater portion, of the heat contained in the vapor escaping from the still, instead of being wasted, as usual, is effectively utilized for the production of power or the performance of other useful work.

10 In that form of apparatus shown in Fig. 2, both of the condensers 5^a and 6^a are contained in the same casing, which is, however, divided into two chambers by means of a partition 22 extending part way across the casing, the chambers communicating with each other through a contracted passage 23 which constitutes the equivalent of the pipe 10 of the apparatus shown in Fig. 1.

15 In the apparatus shown in Fig. 3 both of the condensers 5^b and 6^b, are contained in the same casing, and that portion of the casing containing the condenser 5^b is expanded horizontally beyond the limits of the portion containing the condenser 6^b, in order that an extended surface area may be presented in said condenser 5^b without undue increase in the height of the same.

20 Another modification of my invention is one in which each condenser has an independent supply of water or other condensing agent, the volume or rate of flow 30 of the volume and the rate of flow of the agent in the condenser 5 being less than in the condenser 6, whereby said agent will, 35 in the condenser 5, acquire the desired high temperature, while the flow of the distillate through the condenser 6 will reduce it to the desired low temperature.

25 It will be understood that the various pipes are to be provided with suitable 40 valves, and the other members of the apparatus will be supplied with pressure gages and other equipments usual in such apparatus, and further that no attempt has been 45 made, in the drawing, to show the relative size and location of the different parts of the apparatus.

I claim:—

1. The mode herein described of utilizing 50 waste heat of distillation, said mode consisting in subjecting the vapor from the still to a two-stage condensation, and utilizing the heat of the condensing agent employed in the first stage for the performance of 55 useful work.

2. The mode herein described of utilizing waste heat of distillation, said mode consisting in subjecting the vapor issuing from the still to a two-stage condensation, the 60 volume of condensing agent used in the first stage being less than that used in the second stage, and utilizing heat of the condensing agent for the performance of useful work.

3. The mode herein described of utilizing 65 waste heat of distillation, said mode con-

sisting in subjecting the vapor issuing from the still to a two-stage condensation, the volume of condensing agent used in the first stage being less than that used in the second stage, and utilizing heat of the condensing agent used in the first stage for the performance of useful work.

4. The mode herein described of utilizing waste heat of distillation, said mode consisting in subjecting the vapor issuing from the still to a two-stage condensation, the volume of condensing agent used in the first stage being less than that used in the second stage, and causing heat acquired by the condensing agent to vaporize a power-developing agent having a lower boiling point.

5. The mode herein described of utilizing waste heat of distillation, said mode consisting in subjecting the vapor issuing from the still to a two-stage condensation, the volume of condensing agent used in the first stage being less than that used in the second stage, and causing heat acquired by the condensing agent used in the first stage to vaporize a power-developing agent having a lower boiling point.

6. The mode herein described of utilizing waste heat of distillation, said mode consisting in subjecting the vapor issuing from the still to a two-stage condensation, maintaining a quicker flow of the condensing agent during the second stage than during the first, and utilizing heat of the condensing agent for the performance of useful work.

7. The mode herein described of utilizing waste heat of distillation, said mode consisting in subjecting the vapor issuing from the still to a two-stage condensation, maintaining a quicker flow of the condensing agent during the second stage than during the first, and utilizing heat of the condensing agent used in the first stage for the performance of useful work.

8. The mode herein described of utilizing waste heat of distillation, said mode consisting in subjecting the vapor issuing from the still to a two-stage condensation, maintaining a quicker flow of the condensing agent during the second stage than during the first, and causing heat acquired by the condensing agent to vaporize a power-developing agent having a lower boiling point.

9. The mode herein described of utilizing waste heat of distillation, said mode consisting in subjecting the vapor issuing from the still to a two-stage condensation, maintaining a quicker flow of the condensing agent during the second stage than during the first, and causing heat acquired by the condensing agent used in the first stage to vaporize a power-developing agent having a lower boiling point.

10. The mode herein described of utilizing waste heat of distillation, said mode

consisting in subjecting the vapor issuing from the still to a two-stage condensation, using a portion of the condensing agent in both stages, maintaining a flow of such condensing agent in the second stage in excess of that maintained in the first stage, and utilizing for the performance of useful work heat of the condensing agent which is used in both stages.

11. The mode herein described of utilizing waste heat of distillation, said mode consisting in subjecting the vapor issuing from the still to a two-stage condensation, using a portion of the condensing agent in both stages, maintaining a flow of such condensing agent in the second stage in excess of that maintained in the first stage, and utilizing for the performance of useful work heat of the condensing agent which is used in both stages, as well as heat of the condensing agent which is used only in the second stage.

12. The mode herein described of utilizing waste heat of distillation, said mode consisting in subjecting the vapor issuing from the still to a two-stage condensation, using a portion of the condensing agent in both stages, maintaining a flow of such condensing agent in the second stage in ex-

cess of that maintained in the first stage, 30 and utilizing heat of the condensing agent which is used in both stages of the condensation for the purpose of vaporizing a power-developing agent having a lower boiling point.

13. The mode herein described of utilizing waste heat of distillation, said mode consisting in subjecting the vapor issuing from the still to a two-stage condensation, using a portion of the condensing agent in both stages, maintaining a flow of such condensing agent in the second stage in excess of that maintained in the first stage, and utilizing the heat of the condensing agent which is used in both stages of the condensation, as well as the heat of that portion which is used only in the second stage, for the purpose of vaporizing a power-developing agent having a lower boiling point.

In testimony whereof, I have signed my name to this specification, in the presence of two subscribing witnesses.

FRANK SHUMAN.
